CLAIM

The ornamental design for a frame of an eyewear, as shown and described.

DESCRIPTION

FIG. 1 is a perspective view of a frame of an eyewear showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets

Fig. 1: Perspective view

Fig. 2: Front elevational view

Fig. 3: Rear elevational view

Fig. 4: Left side elevational view

Fig. 5: Right side elevational view

Fig. 6: Top plan view

Fig. 7: Bottom plan view
